[57] CLAIM

The ornamental design for a stand for a portable electric fan with a swivel mount, as shown and described.

DESCRIPTION

FIG. 1 is a front elevational view of a stand for a portable electric fan with a swivel mount;

FIG. 2 is a rear elevational view thereof;

FIG. 3 is a left side elevational view thereof;

FIG. 4 is a section taken from lines 4—4 of FIG. 3;

FIG. 5 is a top plan view thereof; and,

FIG. 6 is a bottom plan view thereof.

The right side elevation is a mirror image of the left side elevation.

The broken-line showing of a fan in FIGS. 1—3, 5 and 6 is for illustrative purposes only and forms no part of the claimed design.
